US0D1091504S

(12) **United States Design Patent** (10) Patent No.: **US D1,091,504 S**
(45) Date of Patent: ** Sep. 2, 2025

(54) **SOUNDBAR**

(71) Applicant: **GUANGZHOU PANYU JUDA CAR AUDIO EQUIPMENT CO., LTD.**,
Guangzhou (CN)

(72) Inventor: **Alex Zhuang**, Guangzhou (CN)

(73) Assignee: **GUANGZHOU PANYU JUDA CAR AUDIO EQUIPMENT CO., LTD.**,
Guangzhou (CN)

(**) Term: **15 Years**

(21) Appl. No.: **29/927,102**

(22) Filed: **Feb. 2, 2024**

(51) **LOC (15) Cl.** **14-01**

(52) **U.S. Cl.** USPC **D14/214**

(57) **CLAIM**

The ornamental design for a soundbar, as shown and described.

DESCRIPTION

FIG. 1 is a first perspective view of a soundbar showing my new design;

FIG. 2 is a second perspective view thereof;

FIG. 3 is a front view thereof;

FIG. 4 is a back view thereof;

FIG. 5 is an enlarged left side view thereof;

FIG. 6 is an enlarged right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the soundbar that form no part of the claimed design.

1 Claim, 9 Drawing Sheets
